UNITED STATES PATENT OFFICE.

JOSEPH LEWIS JONES, OF UTICA, NEW YORK, ASSIGNOR OF ONE-HALF TO
FOSTER BROTHERS, OF SAME PLACE.

CLOTHES-DRIER.

SPECIFICATION forming part of Letters Patent No. 406,100, dated July 2, 1889.

Application filed November 11, 1887. Serial No. 254,930. (No model.)

To all whom it may concern:

Be it known that I, JOSEPH LEWIS JONES, of Utica, in the county of Oneida and State of New York, have invented certain new and useful Improvements in Clothes-Driers; and I do hereby declare the following to be a full, clear, and exact description of the invention, such as will enable others skilled in the art to which it appertains to make and use the same.

10 My invention relates to clothes driers or racks, and more particularly to that class in which the device is adapted to be applied to the wall of a room or house.

The object of my present invention is to 15 provide a simple and neat clothes drier or rack, and one which shall be cheap to manufacture and capable of being stored into compact shape for transportation.

A further object is to so construct the device that the bars thereof which support the clothes can be arranged one above the other in such a manner that the clothes on one bar will not interfere with similar articles placed on other bars.

25 A further object is to construct the several parts of the device so that it can be adapted to support rods of considerable length, and thus accommodate a large amount of clothes, or be so reduced in size as to act simply as a 30 towel-rack, as desired.

With these objects in view my invention consists in the peculiar construction and novel combination and arrangement of parts, as will be hereinafter set forth, and pointed out in the 35 claim.

In the accompanying drawings, Figure 1 is 40 a front elevation of my device, showing one of the supporting-rods removed. Fig. 2 is a detached view of one of the supporting-brackets. Fig. 3 is a view of a modification of supporting-brackets.

A indicate two vertical bars or strips, which are provided with suitable perforations between their ends, through which screws or 45 other fastening devices are adapted to be passed to secure these bars or strips to the wall of the room or house. The bars or strips A are each furnished with a series of plates a, having perforations b near their ends for the reception of screws or nails, by which they are securely attached to the said bars or strips. The

plates a are provided with two outwardly-projecting ears or bosses c, located, preferably, at points between the perforations b of said plates and made with perforations d for the 55 reception of bracket-arms B. These perforated bosses c form sockets for a portion of the bracket-arms B, and, while I prefer this construction, it will be seen that, instead of providing two such bosses, one boss may be 60 made on the plates a, and a socket formed therein for the support of the bracket-arms, as shown in Fig. 3.

The bracket-arms B are preferably made of heavy iron or brass wire and have their ends 65 bent at right angles to their bodies to form downwardly-extending portions e, and dowel-pins f, the portion e being bent in an opposite direction to the dowel-pins f, as shown in Fig. 2, to form depending journals. The 70 portion e of these rods B is of sufficient length to extend through both perforations d of bosses c, and are adapted to turn therein to permit the bracket-arms to have a swinging movement, for a purpose that will be ex- 75 plained.

A series of horizontal clothes-supporting bars C, of wood or other suitable material, are provided on one edge with sockets g near their ends, these sockets being adapted to receive the dowel-pins of the bracket-arms B, upon which latter the bars C are loosely supported.

From this construction it will be seen that the bracket-arms B may be swung on their 85 bearings, and by their loose connection with the cross-bars C these bars may be entirely removed, swung or adjusted nearer to or farther from the wall, as occasion may require.

By adjusting the cross-bars C at different 90 distances from the wall clothes or other articles may be placed upon them without the articles placed on one bar being liable to come into contact with articles upon other bars.

It is evident that the vertical bars A, carrying the bracket-arms B, may be placed at different distances apart, and that supporting-rods C of different length can be employed, thus adapting the device to support a large number of clothes, or be used simply as a 100 towel-rack, as desired.

Slight changes might be made in the con-

structive details of my invention without departing from the spirit thereof or limiting its scope; hence I do not wish to limit myself to the precise details of construction shown and 5 described; but,

Having thus described my invention, what I claim as new, and desire to secure by Letters Patent, is—

In a clothes-rack, the combination, with a 10 series of plates arranged in two vertical rows and in pairs horizontally, each plate having a socket therein, of the arms having downwardly-turned ends loosely resting in said sockets and upwardly-turned ends, horizontal

cross-bars each loosely supported upon the 15 upwardly-turned ends of a pair of arms, the said cross-bars being in different horizontal planes, whereby each bar can be moved toward or away from the wall or other support independently of the other bars, substantially 20 as and for the purpose set forth.

In testimony whereof I have signed this specification in the presence of two subscribing witnesses.

J. LEWIS JONES.
